UNITED STATES PATENT OFFICE.

ELMER M. SHERLOCK, OF PORTLAND, OREGON.

CABINET FOR AUTOMOBILES.

1,263,612.

Specification of Letters Patent. Patented Apr. 23, 1918.

Application filed April 26, 1917. Serial No. 164,806.

To all whom it may concern:

Be it known that I, ELMER M. SHERLOCK, a citizen of the United States, and a resident of Portland, county of Multnomah, 5 State of Oregon, have invented a certain new and useful Improvement in Cabinets for Automobiles, of which the following is a specification.

My invention has for its object the providing of a cabinet which may be affixed to the running board of an automobile, which is adapted in its interior arrangement to carry the camping utensils and provisions, and which is provided with a front cover arranged to be let down so as to provide a table, the inner end of which incidentally provides a cover for the compartments in the bottom of the cabinet.

I attain my object by the device illustrated in the accompanying drawings, in which:

Figure 1 is a front elevation of my cabinet with the cover down;

Fig. 2 is a transverse sectional view.

My invention comprises a case *a*, provided with partitions *b*, *c*, and with further partitions as *d* in the bottom. The front of the case, at the bottom, is closed by a wall *e*, and the upper part of the cabinet is provided with a cover *f*. The latter is hinged at *g* (having reference to the construction shown in Fig. 2). At the inner side of the top of the cover *f* is hinged a supplemental cover-section *h*, extending inward and over the partition *d*, as shown in Fig. 2. The cover *f* is hinged at the bottom to the front wall *e*, the supplemental piece is hinged at the top of the cover, and

the abutting faces of the cover and the supplemental piece are beveled. When access is desired to the pockets in the lower part of the cabinet the supplemental cover-section *h* may be lifted back, as shown in dotted outline in Fig. 2. The cover *f* is held in extended position so as to serve as a table by means of a cable or chain arranged as shown at *i*. When the cover *f* is lifted so as to close the cabinet, the supplemental cover piece *h* (being narrower than the depth of the cabinet) will move inwardly slightly; and when the cover *f* is let down the parts *f*, *g* will assume, automatically, their co-operative positions for providing a table extending into the cabinet.

For holding the cover *f* in its closed position, I provide a staple *j* and hasp *k*. I also provide a ring *l*, by which the cabinet may be suspended. But when placed on the running board of the automobile my cabinet is clamped in place by the clamping bar *m* and thumb screw *n*. *o* are grooved cleats for supporting rods by which to secure dishes in place.

I claim:

A cabinet comprising an open front case, 65 a wall portion closing the lower part of the cabinet, a cover for the open front of the cabinet above said wall, said cover being hinged at the lower inner corner to the top of said wall, a supplemental cover-piece 70 hinged to the upper inner corner of the cover, said supplemental piece being slightly shorter than the depth of the cabinet, and means for supporting the cover in horizontal position.

ELMER M. SHERLOCK.
